PORTABLE MILKER

Arnold I. Terpening, Highland, N. Y., assignor
to The De Laval Separator Company, New
York, N. Y., a corporation of New Jersey

Application April 10, 1947, Serial No. 740,620

5 Claims. (Cl. 230—33)

1

This invention relates to milking machines and more particularly to a portable milker of novel construction wherein a handle, which is used in moving the milker from one location to another, also serves as an integral part of the milking system.

Portable milkers as made heretofore comprise a movable base on which a motor is mounted, and a vacuum pump also mounted on the base and driven by the motor. The milker unit, including the pail, the pneumatic pulsator and the teat cups, can be transported on the base and has a connection to the inlet side of the pump, generally through a flexible hose leading from the base.

It is an object of the present invention to provide a simplified portable milker construction which may be handled with greater facility than has been possible heretofore.

One feature of the invention resides in the provision of a portable milker having a hollow handle supporting a stall cock or other device by which the interior of the handle may be connected to a flexible hose of the milker unit, the interior of the handle also communicating through a duct to the inlet side of the vacuum pump.

Another feature resides in a portable milker of the character described, wherein the duct leading from the interior of the handle to the inlet side of the pump is formed in a hollow base supporting the pump and the motor.

These and other features of the invention may be better understood by reference to the accompanying drawings, in which:

Fig. 1 is a perspective view of one form of the portable milker;

Fig. 2 is a sectional view of the vacuum pump, showing the pump inlet and outlet and also a passage for supplying oil to the pump;

Fig. 3 is a perspective view of one end of the hollow base for supporting the motor and pump;

Fig. 4 is a vertical sectional view of the hollow base;

Fig. 5 is a perspective view of the hollow base, with the cover removed;

Fig. 6 is a perspective view of the cover for the base;

Fig. 7 is a perspective view of a modified form of the portable milker, and

Fig. 8 is a perspective view of part of the milker illustrated in Fig. 7, showing the connection between the hollow handle and the pump.

Referring to Figs. 1 through 6, inclusive, the portable milker comprises a hollow base 10 hav-

2

ing wheels 11 mounted on an axle 12 secured to the base. The base 10 is of a box-like construction having a rectangular bottom and opposing side and end walls, each of which may be a metal plate welded or otherwise connected to the adjoining plates to form an air-tight structure. The top of the box is closed by a movable cover 13 which is secured in position in any suitable manner, a gasket 13a being preferably interposed between the cover and the side walls to make the base airtight.

Mounted on top of the cover 13 is a motor 14, which may be an electric motor energized through a flexible cable 15. A vacuum pump 16 is also mounted on top of the cover 13 and is driven from the motor by a belt 17. The vacuum pump 16 (Fig. 2) is of the type in which the inlet 16a and the outlet 16b are located at the bottom of the pump housing, a pump of this type being disclosed in a co-pending application of C. H. Happgood, Serial No. 597,074, filed June 1, 1945. The pump housing has a generally vertical pipe 16c extending downward from the vicinity of the bearing at one end of the rotor shaft 16d, and a tube 16e extends from the lower end of the oil pipe 16c through an opening 13e in the cover 13, as will be described in detail presently.

Within the hollow base 10 is a vertical, longitudinal partition 10a parallel to the side walls. A generally horizontal partition 10b extends from the partition 10a to the more remote of the two side walls. The partition 10b is located intermediate the top and bottom of the base and is connected at one end to one of the end walls of the base. At its other end, the partition 10b terminates short of the opposite end wall of the base and joins a vertical partition 10c extending to the top of the base, the ends of the partition 10c joining the vertical partition 10a and the side wall to which the partition 10b is connected. The vertical partitions 10a and 10c are provided at the top with extensions of the gasket 13a. Also, the metal-to-metal joints at the edges of the partitions are made air-tight.

The vertical partitions 10a and 10c and the partition 10b partly define a chamber 10d which serves as an oil reservoir, the bottom 10b of which is slightly inclined so that the oil will tend to drain down toward an opening 10e in the adjacent end wall. The oil tube 16e extends down into the oil reservoir 10d through the cover opening 13e, while the outlet 16b of the pump leads down into the oil reservoir through opening 13d in the cover.

The generally horizontal partition 10b divides

the oil reservoir 10d from a chamber 10f in the lower part of the base. The latter chamber serves as a "sani-trap," as will be described in greater detail presently, and communicates with the pump inlet 16a through opening 13c in the cover.

The vertical partition 10a forms one wall of a chamber 10g located on the opposite side of this partition from chambers 10d and 10f. The chamber 10g serves as an exhaust or muffler and communicates with the oil reservoir 10d through an elbow 13b on the cover 13. Air in the muffler 10g is exhausted from the base through a downwardly directed pipe 10h.

The opening 10e from the oil reservoir 10d leads to an oil gauge 19 having at its upper end a removable cap 19a provided with a stem 19b extending down into the interior of the gauge, whereby the oil level in the reservoir may be readily determined by removing the cap. Also, by removing the cap 19a, the supply of oil in the reservoir 10d may be replenished through the gauge. A removable cap 19c is mounted on the lower end of the gauge, and by removing this cap the oil may be drained from the reservoir.

A vacuum regulator 20, which may be of any conventional form, is mounted on the cover 13 and communicates with the "sani-trap" 10f through an opening 13f in the cover. The regulator 20 operates automatically to admit air through cover opening 13f, if the sub-atmospheric pressure in the "sani-trap" 10f should become too low due to withdrawal of air by the vacuum pump through cover opening 13c.

A handle 22 is connected to the base 10 and is used by the operator in moving the portable milker from one location to another. The handle 22 is hollow and is preferably made from metal piping. As shown, the handle is U-shaped and is connected at its ends to the base, one end being connected through an elbow 23 which is welded or otherwise secured over an opening 10i in one side wall of the base. The opening 10i leads into the "sani-trap" 10f above the bottom level thereof and communicates with the inlet 16a of the pump through the cover opening 13c. The other end (not shown) of the handle 22 is connected to the opposite side wall of the base but is closed from the interior of the base.

A connecting device in the form of a stall cock 24 is mounted on the transverse portion of the handle 22 so as to communicate with the interior of the handle, the device 24 being preferably of the type disclosed in Scott Patent No. 2,251,071 dated July 29, 1941. The flexible hose 25 of the milker unit, when applied to the nipple 24a of the stall cock, is connected to the pump inlet 16a through handle 22, "sani-trap" 10f and cover opening 13c, whereby the milker unit is "vacuum" operated in the usual manner.

A platform 26 is hinged to the legs of the handle 22, the free end 26a of the platform being curved downwardly so that when the free-end is lowered it will rest upon the cover 13 of the base. In its lowered position, the platform 26 serves as a support for the milker unit. A leg 27 is secured to the bottom of the base 10 at the end thereof adjacent the handle 22 and serves to support the base when it is stationary. The handle 22 may be provided with a hook 28 for holding a strip cup 29.

In operation, air withdrawn from the milker unit through stall cock 24 passes down through the hollow handle 22 and the elbow 23 into the "sani-trap" 10f, where dust and other particles in the air will settle to the bottom. The air will

then flow up through cover opening 13c to the pump inlet 16a, the compressed air being exhausted from the pump through outlet 16b from which it flows down through cover opening 13d into the oil reservoir 10d. There, a separation of oil from the air occurs, the air then passing through elbow 13b into the muffler 10g from which it is exhausted through pipe 10h. During operation of the pump 16, its rotor assembly is constantly supplied with oil from tube 16e, the lower end of which is below the oil level in reservoir 10d. Since the pressure in the rotor chamber at the upper end of pipe 16c is lower than that in the reservoir chamber 10d, oil will be forced up through tube 16e and pipe 16c to the rotor chamber where it serves as a lubricating and sealing medium, the oil returning to the reservoir through pump outlet 16b.

Because of the hollow handle 22 and its air inlet and outlet connections 24 and 23, respectively, I have provided a portable milker of simplified construction. By locating the stall cock 24 at the upper part of the handle, the hose 25 of the milker unit may be easily maintained well above the floor at all times, which is advantageous in the use of the machine. Moreover, by making the handle 22 an integral part of the milker system, the milker unit may be used at a greater distance from the vacuum pump, without requiring an additional length of hose or other special connection from the region of the pump.

It is to be understood that the construction of the hollow base 10 itself forms no part of my invention, the base construction being disclosed and claimed in a co-pending application of D. F. Ayres, Ser. No. 740,529, filed April 10, 1947.

In the modified form of the portable milker illustrated in Figs. 7 and 8, the base comprises a pair of longitudinal members 30 which may be made of angle iron and are supported in spaced relation on the axle 12 for the wheels 11. A horizontal plate 31 is mounted on top of the members 30 at the front part of the base and supports the motor 14. The pump 16 is supported on a rear plate 32 at a lower level than the plate 31. At its sides, the plate 32 has outwardly extending flanges 32a resting upon the longitudinal members 30. As best shown in Fig. 8, the rotor housing of pump 16 is mounted on a hollow base 33 on the plate 32, the air inlet to the pump being through a pipe 33a connected to a hollow boss on the base 33, and the air outlet from the pump being through a pipe 33b connected to a second hollow boss on the pump base.

Connected to the rear end of one of the longitudinal members 30 is a hollow casting 34, which serves as a leg for supporting the base structure when it is stationary. The casting 34 has a longitudinal passage 34a communicating with one end of the hollow handle 22 connected to the casting. Below this end of the handle, the passage 34a communicates with the pump inlet through a flexible tube 35 connected at one end to a nipple on the casting and at the other end to the inlet pipe 33a. A vacuum regulator 20a is connected to the inlet pipe 33a through a pipe 36 to prevent the sub-atmospheric pressure in the vacuum line, including handle 22, from becoming too low.

The opposite end of handle 22 is connected to the other longitudinal member 30, as by means of a leg casting (not shown), it being understood that the latter end of the handle is closed.

The pump and motor may be enclosed in a removable cover (not shown) having depending

side walls adapted to rest upon the base assembly, 30, 31, 32. The top of such a cover may be used to support the milker unit 38 when moving the machine from one location to another.

Operation of the milker shown in Figs. 7 and 8 is similar to that of the form first described, except that air withdrawn from the milker unit 38 through hose 25, stall cock 24 and handle 22, flows to the pump inlet through the tube 35 which is outside the base, the "sani-trap" being eliminated. Also, while the pump base 33 is provided with an oil reservoir through which the air from the rotor housing is discharged to the exhaust pipe 33b, the separate muffler chamber 10g is eliminated.

I claim:

1. In a portable milker having a movable base and a vacuum pump mounted on the base, the pump having an inlet and an outlet, the combination of a hollow handle connected to the base for use in moving the same from one location to another, a duct leading from the handle to the pump inlet and through which said inlet communicates with the interior of the handle, and a hollow connecting device mounted on a part of the handle remote from the duct and communi- 25

cating with the interior of the handle, said device being adapted for connection with a milker unit.

2. A combination as defined in claim 1, in which said base is hollow and forms the duct through which the pump inlet communicates with the interior of the handle.

3. A combination as defined in claim 1, in which said base is hollow and forms the duct through which the pump inlet communicates with the interior of the handle, the base having an opening in one wall, one end of the handle being connected to said wall around the opening and communicating with said duct through the opening.

4. A combination as defined in claim 1, in which said duct is a pipe located exteriorly of the base.

5. A combination as defined in claim 1, in which the hollow handle is generally U-shaped and is connected at its opposite ends to the base, the hollow connecting device being mounted on the transverse portion of the handle, and said duct being connected to the handle at one end portion thereof.

ARNOLD I. TERPENING.
